UNITED STATES PATENT OFFICE.

WILLIAM L. HANCOCK, OF DALLAS, TEXAS, ASSIGNOR TO THE MURRAY COMPANY, OF DALLAS, TEXAS, A CORPORATION OF TEXAS.

COTTON CHUTE.

Application filed April 17, 1922. Serial No. 553,514.

To all whom it may concern:

Be it known that I, WILLIAM L. HANCOCK, a citizen of the United States, residing at Dallas, in the county of Dallas and State of Texas, have invented certain new and useful Improvements in Cotton Chutes, of which the following is a specification.

My invention is an improved adjustable chute for delivering seed cotton from the gin feeder to either the huller roll box or to the ginning roll box, of a huller gin, as may be desired. My object is to make the adjustment as simple, easy and accurate as may be.

In the drawings:—

Figure 1 is an end elevation partly in section of the general assembly, showing the gin feeder and the upper part of a gin, with the chute interposed between them, showing 20 the chute in two positions, one in dotted lines;

Figure 2 is a front elevation, broken, of the chute, on an enlarged scale;

Figure 3 is a cross-section on line 3—3 of Figure 2; and

Figure 4 is an end view of the chute, showing the parts in a different position.

My chute is especially designed for use between a feeder or feeder-cleaner and a huller gin, i. e. a gin which has two feed openings, one opening to the ginning roll box, as in a plain gin and the other opening to an outer or huller roll box, where seed cotton is given a preliminary treatment before it is carried to the ginning ribs.

In Figure 1, I have indicated the main parts of such a huller gin, A. 1 is the opening to the ginning roll box; 2, the ginning ribs and, 3, the ginning saws; 4 is the opening 40 to the huller roll box and 5 the huller ribs. The gin herein partially illustrated is a pneumatic gin, but whether the gin is a pneumatic or a brush gin is quite immaterial to my present invention. In Figure 1 I have 45 also indicated a feeder mechanism, 6, at the exit opening, 7, of which, my new chute is mounted.

My new chute is made up of a hood, a, and a chute proper, b, pivoted at b⁵ to the sides, a', of hood a. In the outer edges of the ends, b', of chute, b, are notches b², and at the lower end of chute, b, a flap, c, is carried, connected to the chute by slots b³ in

the ends b' of the chute and pins c² in the ends c' of the flap. The slots b³ have at their 55 upper ends retaining notches b⁴.

The hood, a, is secured to the feeder casing 8 and is preferably hinged, as at 8^a. A section a², hinged at a^x is provided and the lower edge of section a² is inturned to form 60 a detent rib a³. At either end of section a², springs a⁴ are connected to the lower edge of hood-section a² and extend outside the side a' of hood a, to the rear edge of which they are connected under tension. 65

It will now be obvious that by lifting outwardly hood section a² against the resistance of springs a⁴ the chute b may be swung upward on its pivots b⁵ and, the section a² being released, the detent a³ will enter 70 notches b² and lock the chute in elevated position. It will also be obvious that, when it is desired to temporarily close the lower end of chute b, the flap c may be turned upward on its pivots c² and lifted upward, 75 until the pivots c², travelling in the slots b³, reach the retaining notches b⁴, in which situation the flap will be retained until it is released and restored to its normal position (see Figure 4). 80

When it is desired to temporarily stop the delivery of seed cotton to the gin, the flap c is turned upward across the exit of the chute and hangs by its pivots c² in notches b⁴ of slots b³. Any of these adjustments 85 may be made rapidly and without any special attention, the simple means employed being self-adjusting. At all positions of the flap c, the surface of the bottom and sides of the flap are in contact with the bottom of chute b and with its sides b', so that at no time is an opening formed between the flap and the chute through which seed-cotton may escape. 90

The operation is as follows: Seed cotton 95 is ejected from the delivery opening 7 of the feeder 6 by the feeder drum into the hood, a, of the chute, from which it passes by gravity to the chute proper, b, and is by the chute directed to the desired opening 100 of the gin. When it is desired to pass the cotton to the ginning roll box, the chute is adjusted as shown in Figure 1, full lines, to deliver into opening 1. When it is desired to direct the seed cotton to the huller 105 roll box, the hood section is adjusted in its

2
elevated position, as in dotted lines, Figure 1, to deliver to opening 4. When it is desired to temporarily close the lower end of the chute, the flap, c, is manually lifted and is guided by the pin and slot connection to the notches b^4 , in which it is suspended until manually released and restored to normal position (see Figure 4).

I claim:

- 10 1. A cotton chute, comprising a hood having a hinged section, carrying a detent member; a spring, tending to draw the hinged section to closed position; a pivoted chute carrying a detent-member to cooper-

ate with the detent member on the hinged section.

2. A cotton chute comprising a hood having a hinged section carrying a detent member on its lower edge; a spring tending to draw the hinged section to closed position; a chute pivoted to the hood ends having a bottom and side walls with a notch in the outer edge of its side wall, to cooperate with the detent on the hinged section, all combined as described.

Signed at Dallas, Texas this the 10th day of April, 1922.

WILLIAM L. HANCOCK.
